UNITED STATES PATENT OFFICE.

RAYMOND W. ROWLEY, OF ST. LOUIS, MISSOURI.

PLASTERER'S FLOAT.

Application filed December 14, 1925. Serial No. 75,233.

The object of this invention is to provide a novel construction of plasterer's float which shall be characterized by simplicity and durability of construction, lightness of 5 weight, and economy in manufacture.

With the above objects in view, the invention resides in a plasterer's float comprising a cork or other suitable face block, a back plate secured thereto in such manner as to 10 prevent any of the connections becoming exposed at the operating face of the float except after a relatively long period and excessive wear, and which connections present no projecting parts on which the plaster can 15 adhere, and a pair of handle supports formed integral with the back plate.

The invention is illustrated in the accompanying drawing, in which—

Figure 1 is a top plan view;
20 Figure 2 is a section taken on the line 2—2 of Figure 1; and

Figure 3 is an enlarged sectional view 25 illustrating one of the plugs and associated hooks connecting the face block and back plate.

Referring to these drawings, the numeral 1 indicates the body or face block of the float, which is preferably made of cork, although it may be constructed of wood or any other 30 suitable material. On its upper side, the body 1 is provided with recesses 2, preferably four in number, located symmetrically at opposite ends of the body, as indicated in Figure 1. The cork body 1 is rectangular 35 in shape and is adapted to be secured to a back plate 3, which is preferably made of aluminum. To this end, the plate 3 is provided with counter-sunk apertures 4 corresponding in number and position to the recesses 2, and which are adapted to receive 40 plugs 5 having heads 6 suitably shaped to be received into the counter-sunk portion of the apertures 4. Each of the plugs 5 is provided with a central screwthreaded aperture 45

7 (Figure 3), which is adapted to receive the screwthreaded shank of a hook 8. The pair of hooks 8 at either end of the float receive, and engage the opposite end portions of, a rod 9, which are inserted into the body 50 1 in transverse passages 10 provided near opposite ends of the body for that purpose. The parts as thus far described are assembled as follows:

The back plate is applied to the top side 55 of the face block 1, the hooks 8 are inserted

in the recesses, the rods 9 are then passed through the openings 10 and through the eyes of said hooks, and then the plugs 5 are screwed onto the shanks of the hooks 8. It will be seen that, when assembled, the heads 6 project only slightly above the upper face 60 of the back plate 3 and thus present no projection on which plaster can engage. Preferably, the heads 6 of the plugs are provided with transverse grooves 11 on their upper 65 ends to facilitate screwing the same by use of a screw-driver or similar instrument.

The handle 12 of the float is mounted by a suitably headed bolt, or the like, 13 in supports 14, which are preferably made by cutting through the back plate 3, as indicated at 15, to provide tongues, and turning the tongues upward. However, the back plate with its supports may be made as a casting 70 instead of being stamped out of a sheet of 75 metal, as described.

It will be apparent from the construction described for connecting the back plate and face block 1, that the latter can never project beyond the operating face of the float 80 until the body 1 has been worn down by extended use; and such excessive wear would only occur after relatively long continued use of the float. When it is necessary to replace the body 1 with a new body, the 85 parts may be readily disconnected by unscrewing the plugs 5 and removing the rods 9 by driving them lengthwise through said body. To facilitate the connection of a new face block to the back plate, I contemplate 90 providing face blocks already prepared with the recesses 2 and transverse passages 10, so that it will require but a very few moments to connect a new face block to the back plate. 95

While I have stated that the back plate and handle supports can be made as a casting, I prefer stamping the same from a sheet of aluminum in the interest of lightness of construction.

I claim:

1. A plasterer's float comprising a face block having two pairs of engaging members located, respectively, near opposite ends thereof and provided with screwthreaded shanks projecting above its upper side, 100 transverse rods passed through the body of said face block and through said engaging members, a back plate applied to the upper side of said face block and having apertures through which said shanks project, screw- 105

threaded members applied to said shanks and screwed against said back plate, and a handle supported on said back plate.

2. A plasterer's float comprising a face block having two pairs of recesses located, respectively, near opposite ends thereof and opening from its upper side, a back plate, having a handle, applied to the upper side of said face block, and means for securing 10 said back plate to the face block comprising engaging members having eyes located in said recesses and screwthreaded shanks projecting upward through apertures in said back plate, rods passed transversely 15 through the body of said face block and through said eyes, and screwthreaded members screwed on said shanks and engaging the upper side of said back plate.

3: A plasterer's float comprising a face block having two pairs of recesses located, respectively, near opposite ends thereof, opening from its upper side and extending to substantially the center of said block, engaging members having eyes located in 20 said recesses and provided with screwthreaded shanks projecting above the upper side of said block, transverse rods passed through the body of said face block and through said eyes, a back plate having 25 counter-sunk apertures corresponding in number and position to said recesses, and applied to the upper side of said face block, screwthreaded plugs screwed on said shanks and having heads shaped to be received in 30 the counter-sunk portion of said apertures, and a handle supported on said back plate.

4. A plasterer's float comprising a face

block having two pairs of recesses located, respectively, near opposite ends thereof, opening from its upper side and extending 40 to substantially the center of said block, and transverse passages extending through said block from side to side thereof and cutting said recesses, engaging members having eyes located in said recesses and screwthreaded 45 shanks projecting above the upper side of said face block, rods inserted in said transverse passages and passing through said eyes, a back plate applied to the upper side of said face block and having counter-sunk 50 apertures corresponding in number and position to said recesses, screwthreaded plugs screwed on said shanks and passing through said back plate into said recesses and having heads shaped to be received into the counter- 55 sunk portion of said apertures, and a handle mounted on said back plate.

5. A plasterer's float comprising a face block having two pairs of engaging members located, respectively, near opposite ends 60 thereof and provided with extensions projecting above its upper side, transverse rods passed through the body of said face block and through said engaging members, a back plate applied to the upper side of said face 65 block and having apertures through which said extensions project, fastening members applied to said extensions and bearing against said back plate, and a handle supported on said back plate.

In testimony whereof, I have hereunto set my hand:

RAYMOND W. ROWLEY.
